INVENTOR

H. L. Hudson

BY

Ames, Leonard
ATTORNEYS

UNITED STATES PATENT OFFICE.

HARRY L. HUDSON, OF BROOKLYN, NEW YORK.

TABLE.

Application filed February 6, 1923. Serial No. 617,305.

To all whom it may concern:

Be it known that I, HARRY L. HUDSON, a citizen of the United States, and resident of the borough of Brooklyn, in the city and State of New York, have invented a new and useful Improvement in Tables, of which the following is a specification.

My invention consists in a table, particularly a kitchen table, provided with a folding chair which, when folded, may be moved into a position out of the way under the table top and which may be drawn out from under the table top and unfolded into position for use.

The object of my invention is to provide certain improvements in the construction, form and arrangement of the several parts whereby the chair may be readily manipulated and which will be very simple, strong and durable.

A practical embodiment of my invention is represented in the accompanying drawings, in which

Fig. 1 represents the table in front elevation, showing the seat in its folded position beneath the table top;

Fig. 2 represents a similar view showing the seat drawn out from under the table top and unfolded into position for use;

Fig. 3 represents a section taken in the plane of the line III—III of Fig. 1;

Fig. 4 represents a section taken in the plane of the line IV—IV of Fig. 2; and

Fig. 5 represents a section taken in the plane of the line V—V of Fig. 2.

The folding seat comprises a sliding member 1; a supporting member 2; a seat member 3 and a leg member 4. The supporting member 2 is hinged at 5 to the outer edge of the sliding member 1; the seat member 3 is hinged at 6 to the outer edge of the supporting member 2; and the leg member 4 is hinged at 7 to the under side of the forward portion of the seat member 3.

The sliding member 1 is provided with oppositely arranged horizontally disposed pins 8 which are arranged to slide on tracks 9 carried by the peripheral apron 10 depending from the table top 11.

A supporting bar 12 is carried by the apron 10 parallel to and below the tracks 9 for supporting the chair in its folded position under the table top 11 within the apron 10 as will hereinafter appear.

The seat portion 3 may be provided with

a finger recess 13 for facilitating the manipulation of the chair.

The front member of the apron 10 is provided with a shouldered slot 14 through which the folded chair is moved into and out of its operative position, said slot 14 being provided with shoulders 15 on which the sliding member 1 rests when the chair is withdrawn and unfolded for use.

Stops 16 at the front ends of the tracks 9 serve to engage the pins 8 of the sliding member to limit the outward movement of the sliding member when the folded chair is withdrawn into position to be unfolded for use.

Presupposing the chair to be in its folded position under the table top within the apron 10, the parts are manipulated to bring the chair into position for use as follows: The projecting outer edge of the seat portion 3 of the chair is grasped and the folded chair is withdrawn through the slot 14 until the outward movement is stopped by the engagement of the pins 8 with the stops 16 leaving the sliding member resting on the shoulders 15 of the slot 14. The supporting member 2, seat member 3 and leg member 4 are then unfolded to bring the leg member into engagement with the floor and to bring the supporting member into engagement with the outer face of the apron 10. The chair is then ready for use and is very rigidly supported.

To return the chair to its inoperative position, the supporting and seat members are brought into horizontal alignment with the sliding member and the leg member is then folded against the seat member. The chair is then moved inwardly through the slot 14 to its position underneath the table top within the apron 10, it being understood that the bar 12 serves to support the folded chair in this position.

It is evident that various changes may be resorted to in the construction, form and arrangement of the several parts without departing from the spirit and scope of my invention; hence, I do not wish to limit myself to the particular embodiment herein shown and described, but

What I claim is:

1. The combination with a table, of a folding chair comprising a member slidable in guides beneath the table top, a supporting member hinged at its rear edge to the

front edge of the sliding member, a seat member hinged at its rear edge to the front edge of the supporting member, and a leg member hinged at its upper edge to the 5 front edge of the seat member.

2. The combination with a table, of a folding chair comprising a member slidable in guides beneath the table top, a supporting member hinged at its rear edge to the front 10 edge of the sliding member, a seat member hinged at its rear edge to the front edge of the supporting member, and a leg member hinged at its upper edge to the front edge of the seat member, the chair when folded 15 having its sliding, supporting, and seat members arranged in horizontal alinement with the leg member folded underneath the same.

3. The combination with a table provided 20 with an apron having a shouldered slot, of a folding chair movable into and out of operative position through said slot, said chair comprising a member slidable in guides beneath the table top, and arranged, when 25 pulled out to the limit of its forward movement, to rest on the shoulders of said slot, a supporting member hinged at its rear edge to the front edge of the sliding member in position when unfolded to rest against the

apron, a seat member hinged at its rear edge to the front edge of the supporting member and a leg member hinged at its upper edge to the front edge of the seat member. 30

4. The combination with a table provided 35 with an apron having a shouldered slot, of a folding chair movable into and out of operative position through said slot, said chair comprising a member slidable in guides beneath the table top, and arranged, when 40 pulled out to the limit of its forward movement, to rest on the shoulders of said slot, a supporting member hinged at its rear edge to the front edge of the sliding member in position when unfolded to rest against the 45 apron, a seat member hinged at its rear edge to the front edge of the supporting member and a leg member hinged at its upper edge to the front edge of the seat member, the chair, when folded, having its sliding, 50 supporting and seat members in horizontal alinement, and the leg member folded underneath the same.

In testimony that I claim the foregoing as my invention, I have signed my name 55 this 31st day of January 1923.

HARRY L. HUDSON.
